UNITED STATES PATENT OFFICE.

WILLIAM STEPHEN FITZGERALD, OF CHICAGO, ILLINOIS, ASSIGNOR TO INTERNATIONAL HARVESTER COMPANY, A CORPORATION OF NEW JERSEY.

SAND-CUTTER.

1,330,070.

Specification of Letters Patent.

Patented Feb. 10, 1920.

Application filed July 1, 1918. Serial No. 242,875.

To all whom it may concern:

Be it known that I, WILLIAM S. FITZGERALD, a citizen of the United States, residing at Chicago, in the county of Cook and State of Illinois, have invented certain new and useful Improvements in Sand-Cutters, of which the following is a full, clear, and exact specification.

This invention relates to sand cutting machines for foundry use.

In the preparation of sand in foundries for use in molding, it is necessary to work the sand and mix it by means of shovels or like implements, which are used to toss the sand in such a way as to insure a thorough working and mixing thereof, whereby it is left in the desired tempered and homogeneous condition.

The object of my invention is to provide means for working and mixing the sand that will be simple and strong in construction and efficient in operation.

Another object is to provide sand mixing means which shall be made up of a minimum number of operative parts and will perform its sand mixing operation in a manner simulating very nearly the hand mixing.

With the above objects in view my invention is embodied in a construction in which a plurality of sand mixing elements, such as shovels, are arranged at an angle to the line of draft, and are operated in such a manner that as the machine is propelled across the floor of the foundry, the sand will be thrown at an angle to the line of draft, and left in the form of a ridge.

In the construction illustrated in the accompanying drawings a plurality of sets of sand mixing elements or shovels has been illustrated, these sets being arranged at an angle with relation to each other and to the line of draft, and being operated in such a manner that one set will throw the sand in a direction at an angle to that of the other set, thereby attaining the desired end.

In the accompanying drawings wherein I have illustrated one embodiment of my invention,—

Figure 1 shows a top plan view of the sand mixer;

Fig. 2 is a vertical section taken on line 2—2 of Fig. 1;

Fig. 3 is a rear elevational view of the construction shown in Fig. 1; and

Fig. 4 is an enlarged detail view showing

the driving connections from the motor to the crank shaft.

The frame of my machine is substantially rectangular in shape and is made up of horizontally disposed side members 10 and 11 connected at their front ends by a cross member 12. The members 10 and 11 are also provided at their front and rear ends and intermediate their ends with vertically extending members 13, 13' and 14, which in turn are connected at their upper ends by longitudinally extending members 15 and 16 and by front and rear members 17 and 18. Members 15 and 16 are connected intermediate their front and rear ends by cross members 19 and 20, and vertical members 13 and 14 are connected intermediate their upper and lower ends by longitudinally extending members 21 and 22. In addition to the cross members above described, a further cross member 29 is secured to the longitudinally extending side members 21 disposed at the ends of said member 29 and is secured intermediate its ends by a brace 30 to the upper front cross member 17.

The frame work above described is carried by supporting wheels, the front wheels 23 being journaled on a shaft 24 which is carried by brackets 25 secured to the longitudinal frame members 10 and 11. The rear wheels 26 are mounted on stub shafts 27 which are carried by bracket members 28 secured to the rear ends of the longitudinally extending side members 10 and 11.

From the above description it will be seen that the frame is substantially box shaped and is of skeleton construction, the frame members being preferably formed of angle iron.

The sand mixing elements will now be described.

In the embodiment of the machine illustrated in the drawings, the sand is mixed by means of a series of shovels 31 which are manipulated by means of crank arms and crank shafts hereinafter described. The shovels 31 are provided with shanks 32 which extend through and are secured to blocks 33 rotatably mounted on the crank arms 34 formed on the crank shafts 35. As illustrated, the shanks 32 are adjustable in the blocks 33 by means of set screws 36 whereby their height may be regulated. The crank shafts 35 are journaled in brackets 37 secured at their outer ends to the lon-

itudinally extending members 22 and the inner ends of the crank shafts are journaled in brackets 38 secured to cross braces 39 which are bolted to the members 19 and 20. The crank shafts as clearly illustrated in Figs. 1 and 3, are arranged at an angle to each other and are connected at their inner ends by means of intermeshing bevel gears 40 and 41. The left hand crank shaft (looking at Fig. 3) on which is secured the bevel gear 40, is driven by means of a sprocket wheel 42 which is connected by a chain 43 to a sprocket 44 carried by a stub shaft 45. This stub shaft also carries a spur gear 46 which meshes with a gear 47 secured to a shaft 48 of a motor 49 which may be of any suitable construction. This motor is bolted to cross braces 50 connected at their ends to the brace 29 and cross member 19.

It should be understood that this driving means is shown merely for the purpose of illustration and that any other suitable driving power may be employed.

In the embodiment of my invention illustrated in the drawings, each of the two sets of shovels is shown as made up of three shovels, the middle shovel of each set of three being mounted on a crank disposed at an angle of 180° to the crank arms which carry the two outer shovels. The shovels at one side of the machine are also mounted on crank arms disposed at an angle of 90° with respect to the crank arms of the shovels at the opposite side. By mounting the shovels in this manner it will be seen that the shovels of the two sets engage the sand alternately and that in a single set the middle shovel is disposed in its highest position when the two remaining shovels are disposed in their lower position. In each instance the shank portions 32 of the shovels are connected by means of links 51 to brackets 52 carried by the bar 29. This construction causes the shovels to move in a combined vertical and horizontal direction, their movement describing an orbital path in which the upper portion of the orbit is substantially flat and the lower portion is oval.

By means of this construction the shovels pass into the sand and move through the sand in a substantially vertical position having an abrupt withdrawal movement which is followed by a long forwardly and downwardly inclined motion.

By mounting the sand mixing elements or shovels at an angle to the line of draft, I have provided a construction by the use of which the sand will be thrown into a pile, the opposing sets of shovels forming it into a ridge.

A brief statement of the operation of the machine will now be given.

The motor is first set in operation by a suitable controlling switch and the machine

is then propelled through the sand by any suitable means of propulsion and may be manipulated by hand or by a separate power unit designed for this purpose. As the machine is moved in the direction of the arrow shown in Fig. 1, the shovels will be moved through their cycle by means of power derived from the motor, kicking the sand rearwardly and leaving it in a ridge substantially in alignment with the center of the machine. The orbital movement given to the shovels through their link connection 51 with the frame and their pivotal connection with the cranks, thoroughly mixes and kneads the sand and leaves it in a homogeneous and friable condition.

While I have in the above specification described one embodiment which my invention may assume, it should be understood that the invention is capable of modification, and that modifications may be employed without departing from the spirit and scope of the invention as expressed by the following claims.

I claim—

1. A sand cutting machine including a frame, crank shafts carried by said frame and arranged at an angle to each other, sand cutting shovels carried by said crank shafts, and means including said shafts for moving said shovels downwardly into a mass of sand, rearwardly through said sand and toward the longitudinal center of the machine, upwardly away from said sand, and forwardly, whereby the sand will be deposited in a central ridge.

2. A sand cutting machine including a frame and a plurality of sand cutting elements independently carried by said frame and disposed at an angle to the line of draft, and means for giving said elements a combined vertical and horizontal movement, said horizontal movement being directed toward the longitudinal center of the machine.

3. A sand cutting machine including a frame and a plurality of sand cutting elements carried by said frame and disposed at an angle to the line of draft, and means including a series of crank arms for giving said elements a combined downward and inward movement toward the longitudinal center of the machine.

4. A sand cutting machine including, in combination, a frame and a plurality of sand cutting elements, a crank shaft journaled on said frame and having oppositely disposed crank arms, said sand cutting elements being operatively carried by said oppositely disposed crank arms and moving downwardly and inwardly toward the longitudinal center of the machine.

5. A sand cutting machine including, in combination, a plurality of sets of angularly disposed sand cutting elements, and means for giving said elements a combined

vertical and horizontal movement in a direction to deposit the sand in a central ridge.

6. A sand cutting machine including, in combination, a plurality of sets of oppositely disposed, angularly arranged sand cutting elements, and means for giving said elements a combined vertical and horizontal movement toward the center of the machine, certain of the elements of one set being disposed in their lower position while certain of the elements of the opposite set are disposed in their elevated position.

7. A sand cutting machine including, in combination, a plurality of oppositely disposed angularly arranged sets of sand cutting elements, means including a series of crank arms for giving said elements an orbital movement in a direction to deposit the sand in a central ridge.

20 8. A sand cutting machine including, in combination, a frame, a plurality of crank shafts carried by said frame and disposed at

an angle with respect to each other, crank arms carried by said crank shafts, the crank arms on one of said shafts being disposed at 25 an angle with respect to the crank arms on the shaft arranged at an angle with respect thereto, sand cutting elements operatively carried by said crank arms, and means including said crank shafts for moving said 30 elements downwardly and inwardly toward the longitudinal center of the machine.

9. A sand cutting machine including a frame, crank shafts carried by said frame and arranged at an angle to each other, sand 35 cutting shovels carried by said crank shafts, and means including said shafts for giving said shovels an abrupt downward movement into a mass of sand, and a gradual rearward and upward movement whereby 40 said shovels will deposit the sand in a central ridge.

In testimony whereof I affix my signature.

WILLIAM STEPHEN FITZGERALD.
